UNITED STATES PATENT OFFICE

130,810

DESIGN FOR A LIGHTING FIXTURE

Frederick C. Baker, Portland, Oreg.

Application June 23, 1941, Serial No. 101,627

Term of patent 3½ years

To all whom it may concern:

Be it known that I, Frederick C. Baker, a citizen of the United States and a resident of Portland, county of Multnomah, and State of Oregon, have invented a new, original, and ornamental Design for a Lighting Fixture, of which the following is a specification, reference being had to the accompanying drawing, forming a part thereof.

In the drawing:

Figure 1 is a perspective view of a lighting fixture showing my new design, the view being

taken from a point located below the fixture; and

Figure 2 is a corresponding perspective view of the same, taken from a point located above the fixture.

The side and end of the fixture not seen in the views is the same as the corresponding side and end shown.

I claim:

The ornamental design for a lighting fixture, substantially as shown and described.

FREDERICK C. BAKER.
